ELECTRICAL FIXTURE.

972,577.

Specification of Letters Patent. Patented Oct. 11, 1910.

Application filed June 17, 1909. Serial No. 502,742.

To all whom it may concern:

Be it known that I, FRANK E. SEELEY, a citizen of the United States of America, and residing at Bridgeport, in the county of Fairfield and State of Connecticut, have invented certain new and useful Improvements in Electrical Fixtures, of which the following is a specification.

My invention relates to electrical fixtures and particularly to pendent sockets, switches, etc., my object being to provide a novel and efficient construction to take the strain of the fixture from the terminal connections to the leading-in wires.

In the accompanying drawings, Figure 1 is a perspective of the body of a lamp socket to which my invention is applied in one form; Figs. 2, 3 and 4 are vertical sections through portions of the sockets having caps of various forms embodying my invention; Fig. 5 is a broken vertical section through a pendent switch to which my invention is applied in another form; and Fig. 6 is a vertical section through a similar rosette.

In its main features the socket shown in Figs. 1 to 4 is of the usual construction with screw shell S and upper and lower insulating buttons A and B between which the switch mechanism may be located. The terminals T are located in recesses in the side of insulating body with wire grooves G opening into the same. On the top of the button A I now propose to form a relatively sharp flange F preferably annular as shown in Fig. 1, over the outer face and upper edge of which the wire coming from the terminal must pass. Coöoperating with this flange I propose to form in connection with the cap C suitable means for depressing the wire so that the latter is forced into a sharp U bend over the edge of the flange F. This may be accomplished in various ways. Thus for instance in Fig. 2, the insulating bushing I is extended so far down into the interior of the cap that it depresses the wires W into the well formed by the flange F thereby securing the requisite sharp bend over the edge of the latter. A sharp bend over the edge of the bushing is also given to the wire so

that in fact an S bend at least one loop of which is made quite sharp, is effected. In Fig. 3 the insulating bushing K screws into a metallic bushing L and the distance which it extends into the interior of the shell may

thus be regulated. This is a valuable modification since it permits the adjustment of the strain relief members to suit different makes and sizes of wire which may be employed in wiring up the fixture. In Fig. 4 the customary metallic bushing M with insulating lining N is shown, the bushing M however being provided with a depending skirt m which engages and depresses the wires in like manner as in the constructions just described.

In Fig. 5 the device is applied to a pendent switch. In this modification in addition to the flange F I propose to provide a central boss f, thus forming a channel H into which the annular skirt R of the bushing forces the wires. It will be observed that the boss f not only insures an S bend, both loops of which are sharp since the wire is directed sharply upward by the boss, but that it offers another friction surface against which the wires bear and thus still further lessens the strain upon the binding posts.

Obviously the flange F need not be continuous but may be of any desired shape and size, although it is preferably continuous as shown since in this form the wires cannot be carried out of the cap without passing over the flange, and it is thus impossible to wire up the fixture without bringing the strain relief feature into play. Nor is it necessary that the flange be formed in the position indicated.

I do not limit myself to the embodiments of my invention illustrated, but

I claim,

1. An electric device having separable members, means for uniting the same, wire terminals on one member, one of said members being recessed and the other member being provided with a projection tending to enter said recess, said projection and recess being so located that a wire connected to one of said terminals is forced into a relatively sharp U-bend over said projection when said members are united.

2. An electric device having a body part provided with wire terminals and an incasing shell therefor, said body and shell having strain relief means for the wires leading to said wire terminals, comprising a projection on one part and a corresponding recess on the other part into which said projection tends to enter whereby a wire engaged be-

tween said strain relief members is forced into a relatively sharp U-bend over the projection, substantially as described.

3. An electric device having a body part provided with terminals, a flange on said body part, in combination with a detachable shell incasing said body part and a projection thereon for pressing into the recess adjacent said flange on the body part a wire leading to a terminal on the latter.

4. An electric device having a body part with wire terminals and a detachable shell incasing the same, together with means on said shell and body part tending to interlock when the shell and body parts are united and thus form the wires leading to said terminals into a relatively sharp U-bend over said projection.

5. An electric device having a body part, with wire terminals, a continuous raised flange on one end of said body part, in com-

bination with a shell incasing the latter and means in connection with said shell for forcing the wires leading to said terminals into a sharp U-bend over said flange.

6. An electric device having a body part, with wire terminals, a continuous raised flange on one end of said body part, a boss cooperating with said flange to form a channel, in combination with a shell incasing said body part and means in connection with said shell for forcing down into said channel the wires leading to said terminals whereby a sharp U-bend is formed thereon, substantially as described.

In testimony whereof I have signed my name to this specification, in the presence of two subscribing witnesses.

FRANK E. SEELEY.
